ATTORNEY

UNITED STATES PATENT OFFICE

CHARLES RINGEL, OF NORTH HAWTHORNE, NEW JERSEY, ASSIGNOR TO THE SUPER-HEATER COMPANY, OF NEW YORK, N. Y.

LOCOMOTIVE FIRE BOX

Application filed January 2, 1930. Serial No. 418,050.

My invention relates to fire boxes of the water tube type and aims to provide a fire-box for burning liquid or pulverized fuel and having a relatively large heating surface. The novel features of the invention are pointed out with particularity in the appended claims. My invention, however, together with further objects and advantages, will best be understood from a detailed description of a locomotive fire-box embodying the invention and such a description will now be given in connection with the affixed drawings, in which

Fig. 1 is a sectional elevation taken on a vertical plane through the fire-box of a locomotive and looking toward the front of the locomotive, parts being omitted for purposes of illustration; Fig. 2 is a section on the line 2—2 of Fig. 1, the forward portion of the boiler being omitted.

The illustrative embodiment of the invention shown in the drawings comprises a locomotive boiler having a barrel 4 from the upper portion of which extends rearwardly a steam and water drum 6 into which are expanded two groups of outwardly and downwardly extending water tubes 8, 8 which form side and rear walls of the fire-box. At their lower ends most of the tubes 8 are connected to a hollow foundation ring 10 which lies in a horizontal plane and defines the fire-box in plan. The forward transverse portion of the ring 10 is connected into the bottom of the barrel 4 by a pipe 12 so that water may circulate from the barrel 4 through the ring 10 upwardly through tubes 8 into the drum 6 and thence back to the barrel. It is preferred also that an inner transverse leg 14 be provided for the ring 10 and that arch tubes 16 be so connected into the leg 14 as to extend forwardly and upwardly to a connection with the drum 6, tubes 16 affording, in addition to their water heating surface, a support for fire brick 18 separating the rear portion 20 of the fire-box from a front combustion chamber 22

immediately in rear of the rear flue sheet 24 of the boiler.

In locomotives using oil or pulverized fuel it is customary to provide a pan lying below the mud ring of the fire box and I have illustrated a pan 26 supported from the ring 10 at its rear end by plate 28 (Fig. 2) and at its front end by plate 30 which is secured to the transverse leg 14. The side edges of pan 26 are supported from the sides of ring 10 by inclined plates 32, 32, (Fig. 1) the upper ends of which are bent horizontally at 33, 33 and rest on the inner edges of the top of the ring. The inner faces of the pan 26 and the plate 28 are protected by fire brick 34 while the forward plate 30 is apertured to receive a burner 36 which discharges rearwardly above the pan, the products of combustion being diverted upward by the rear layer of brick 34 and passing up between the tubes 16 into the combustion space 22 from which they are carried forward by the fire tubes 38 in the barrel 4. Preferably the space between the front member of the ring 10 and the leg 14 is left open as appears at 39 so that secondary air may pass upwardly into the combustion space 22.

In order to increase the water heating surface of a locomotive such as that above described, there are provided two groups of water tubes 40, 40, which lie parallel to the inclined plates 32, a layer of asbestos lagging 42 being inserted between each group of tubes 40 and the adjacent plate 32. At their lower ends, the tubes 40 connect into headers 44, 44 extending longitudinally of the fire-box above the pan 26 just inside the side edges thereof. Headers 44 are supplied with water from the ring 10 and for this purpose I have shown tubular connections 46, 46 one at each end of each header 44. The rear connections 46 run upwardly from the headers 44 into the rear transverse run of the ring 10 and the front connections 46 extend upwardly from the headers 44 into the transverse leg 14.

14. Connections 46 serve not only to supply headers 44 with water, but also help to support headers 44. An outlet for steam formed in the tubes 40 is provided at their upper 5 ends by means of headers 48, 48 into which the tubes 40 are connected and which run parallel to the side walls of the fire-box just above the ring 10. To provide an outlet for steam from headers 48 a few of the water 10 tubes in groups 8, 8, are bent inwardly at their lower ends as indicated at 8' and connected into the headers 48. Preferably the tubes 40 are of the bifurcated type as appears clearly from Figs. 1 and 2. Plates 50, 15 50 may be employed to extend between the inclined plates 32 and the bottom of ring 10 to reinforce plates 32.

While I have shown the burner at the front end of the fire-box, it may be placed in any 20 convenient location. It will be understood, also, that my improvements are adapted for use in any water tube boiler irrespective of the fuel burned therein.

I claim:

25 1. A fire-box having a hollow base ring, water tubes forming walls of the box and some of which connect into said ring at their lower ends, headers parallel to the sides of the fire-box and near the plane of said ring, 30 lower headers below said headers, water tubes extending upwardly from said lower headers and connecting said lower to said first headers, tubular connecting means between the ends of said lower headers and said ring, 35 means for supplying water to said ring, and means for taking off steam from said first headers.

2. A fire-box as set forth in claim 1 and in which the means for taking off steam from 40 the first headers comprises some of the tubes forming the walls of the fire-box.

3. The fire-box as set forth in claim 1, together with a pan below the lower headers, and a burner for fluid fuel set at the forward 45 end of said pan and discharging rearwardly above it.

4. A fire-box having a hollow base ring, water tubes forming walls of said box most of which connect into said ring at their lower 50 ends, headers parallel to the sides of said fire-box and near the plane of said ring, lower headers inside and below said headers, water tubes inclined upwardly and outwardly from said lower headers and connecting said lower 55 to said first headers, tubular connecting and supporting means between the ends of said lower headers and said ring, means for supplying water to said ring, means for taking off steam from said first headers, a pan below 60 said lower headers, a burner for fluid fuel set at the forward end of said pan and discharging rearwardly above it, insulating material outside said inclined tubes, and plates between the pan and ring and outside said insulation.

5. A fire-box as set forth in claim 1 and in which the second mentioned water tubes are inclined outwardly from the lower headers.

6. A fire-box as set forth in claim 1 and 70 in which the second mentioned water tubes are inclined outwardly from the lower headers, and in which the means for taking off steam from the first header comprises some of the tubes forming walls of the fire-box. 75
